UNITED STATES PATENT OFFICE.

JAMES M. MARTIN, OF KNOXVILLE, TENNESSEE, ASSIGNOR OF ONE-HALF
TO WILLIAM P. HOOD, WILLIAM M. HOOD, AND THOMAS NUTT, OF SAME
PLACE.

DESIGN FOR A ROCKER-CUSHION FOR ROCKING-CHAIRS OR CRADLES.

SPECIFICATION forming part of Design No. 31,493, dated September 5, 1899.

Application filed June 19, 1899. Serial No. 721,147. Term of patent 14 years.

To all whom it may concern:

Be it known that I, JAMES M. MARTIN, a citizen of the United States, residing at Knoxville, in the county of Knox and State of Tennessee, have invented and produced a new and original Design for a Rocker-Cushion for Chairs or Cradles, of which the following is a specification.

This invention relates to a new and original design for a rocker-cushion for rocking-chairs and cradles, which will be more fully herein-after referred to.

The essential feature of the design resides in the rocker-cushion having a semi-elliptical lower portion with flat upper faces and a T-shaped upper portion also provided with a flat upper face and flat side faces and edges.

The figure in the accompanying drawing represents a perspective view of a rocker-cushion embodying the features of the design.

Referring to the drawing, 1 designates a cushion comprising a T-shaped upper portion 2 and a rounded lower portion 3, approximately semi-elliptical in cross-section and 25 having a convexed lower face 4 and opposite

flat side faces 5, arranged at the top of the lower or bottom portion of the cushion. The T-shaped upper portion of the cushion is provided with a central vertical web 6, having horizontal flanges 7, extending from opposite 30 sides of the upper extremity thereof. The side faces of the web are flat and the upper face of the T-shaped portion is straight in cross-section, and the side edges of the flanges are also flat. The lower faces of the laterally- 35 disposed flanges are parallel with the oppositely-disposed flanges at the top of the lower portion of the cushion.

What is claimed is—

The design for a rocker-cushion for rocking-chairs and cradles, herein shown and described.

In testimony that I claim the foregoing as my own I have hereto affixed my signature in the presence of two witnesses.

JAMES M. MARTIN.

Witnesses:
